UNITED STATES PATENT OFFICE.

GEORGE BAEHR, OF IRWIN, PENNSYLVANIA.

EXPANSIBLE COMPOSITE ROLL.

Application filed July 21, 1922. Serial No. 576,491.

To all whom it may concern:

Be it known that I, GEORGE BAEHR, a citizen of the United States, and a resident of Irwin, in the county of Westmoreland and 5 State of Pennsylvania, have invented a new and useful Improvement in Expansible Composite Rolls, of which the following is a specification.

This invention relates to composite rolls. 10 More particularly it relates to means for building up or reducing the size of the roll body upon which segmental forming members are positioned. The objects of the invention are to provide means for varying 15 the size of the roll body, to compensate for change of size of the forming segments, and to increase or decrease the effective circumference of the forming groove or the length of any portion thereof, whereby to vary the 20 length of articles, or of certain portions thereof, finished therein.

The uses and advantages of the invention will more fully appear in the following specification and from the drawing, wherein 25 Fig. 1 is a cross section through a composite roll; Fig. 2 is a similar cross section showing the forming segments spaced away from the roll body by a special liner; Fig. 3 is an enlarged partial section on the line 3—3 of Fig. 1; Fig. 4 is an enlarged partial section on the line 4—4 of Fig. 2; Fig. 5 is an enlarged partial section on the line 5—5 of Fig. 2; Figs. 6 and 7 show a modification having to do with means for compensating for lateral reduction of the forming 35 segments, and Fig. 8 is a vertical section through a roll showing an additional forming member added thereto to fill out the gap formed in the forming members by placing 40 a liner thereunder.

Composite rolls made up of a roll body or spindle upon which are clamped one or more series of segmental facing members, the latter having a forming groove in their 45 surfaces adapted to shape a hot bar as it passes between the rolls, are not new. The present invention is an improvement applicable to such rolls.

When composite rolls are used for forming certain articles of varying cross section, such as crow bars, tie rods for street railway 50 tracks, automobile axles, and the like, it is

frequently desirable to slightly increase or decrease the length of the finished article, or to vary the length of one portion thereof. 55 For example, street railway tie rods are ordinarily made with a flattened body portion, and round end portions. The latter are threaded to extend through the web of the tracks and carry terminal nuts. Some specifications vary the relative length of this threaded portion and the flattened body portion a small amount. Therefore, it is highly desirable to be able to vary the total length of such an article, or to vary the relative 60 lengths of the round and flattened portions, by a small amount, without a new pair of rolls. This may be done by the present invention.

Furthermore, after such rolls have been 70 used for a certain length of time the grooves become worn, and require redressing. This is ordinarily done by machining out the old groove. In order not to increase the size of the finished product it is necessary to turn 75 down either the entire flat face of the segmental members before recutting the groove, or else to turn down the meeting faces of the two segments before recutting the groove.

In either case a certain amount of space 80 results and must be taken care of. The present invention provides means for doing this, as well as for slightly varying the effective size of the rolls, or the effective 85 length of different portions of the forming groove.

Referring to the drawings, a roll body 1 is illustrated having a supporting head 2 upon which the segments are mounted. The preferred arrangement of this composite roll is shown in Figs. 3, 4, and 5, and comprises a fixed collar member 3 having an undercut beveled face 4. At the opposite side of the roll an annular member 5 having a corresponding undercut portion 6 is adapted to cooperate with the fixed collar 3. Bolts 10 extend through the collar and into the roll body, and are adapted to clamp the ring member against the roll, in obvious manner. 90 The under edge of these rings has a flange 95 7, which engages the underside of the body portion 2, as illustrated.

The preferred form of facing segments

is shown in Figs. 3, 4 and 5, comprising beveled edge segments 8 and 9 arranged in cooperating pairs with the forming groove cut out from their meeting edges. Segments 8 form a semi-circular groove as shown in Figs. 3 and 4, segments 9 a flattened groove, as shown in Fig. 5.

A modification is shown in Figs. 6 and 7, in that the facing members do not have beveled edges, but are retained under the collar 3^a which has a straight-faced overlapping portion 4^a, and the ring 5^a, which has a corresponding straight-faced overlapping portion 6^a.

In Figs. 1 and 3 the preferred form of set up is illustrated. When this roll has been used until the groove requires dressing, the segments 8 and 9 are machined off along their meeting edges. This reduces the groove between them, which is then machined out to its former size. The result is to narrow the segments. This may be compensated for by bringing the ring 5 in closer to secure the desired clamping action. Or the dressing of the groove may be accomplished by turning down the outer faces of the segments, and then re-cutting the groove to its original size and depth. In that case a liner member 11 is positioned on the roll body beneath the segments so as to build them out to their original circumference.

In the form shown in Figs. 6 and 7, the redressing of the groove is effected by machining off the meeting edges of the segments, bringing them together, recutting the groove, and filling the resulting space by washer rings 12, as illustrated in Fig. 7.

When it is desired to slightly increase the length of an article being rolled, this may be done by putting the liner 11 under the facing segments as shown in Fig. 2. This builds them out and by increasing the effective diameter of the roll lengthens the article formed at each revolution thereof. The gap that is formed in the segments when the liner is interposed, either after turning off the outer faces as illustrated in Fig. 4, or when the circumference of the forming face is to be actually increased, as where the liner is used with segments that have not been turned down, may be filled by substituting a longer segment 8 or 9, or by adding a special segment 13 as shown in Fig. 8. Obviously this added segment may be similar to either segments 8 or 9 according to which portion of the rolled article is to be lengthened.

Thus when specifications call for tie rods of slightly greater length than those which would be made by the rolls as shown in Fig. 1, I am enabled to produce them with the same rolls, and the same segmental forming members, by removing the segments, placing a liner member 11 around the roll body, and then replacing the segments, to-

gether with an additional segment, as for example 13, or by substituting longer segments for some of those removed. By this means the circumference of the roll body is increased, and consequently the length of the finished rod.

When the liner member 11 is added, the diameter of the carrying roll, that is to say the effective diameter of what has been referred to as the roll body is changed, and the inner faces of the segmental forming or face members will not fit exactly. But these members are made of considerable length, and it has been found that the pressure of the overhanging clamping rings, with a blow of a hammer in the outer middle face will overcome this by springing the middle of the segment inward so that it seats accurately.

I claim:

1. The combination with a composite roll comprising a roll body and removable forming segments adapted to be carried thereon, of a removable liner member adapted to fit between the roll body and segments, whereby to vary the circumference of the roll body carrying the segments.

2. The combination with a composite roll comprising a roll spindle, a plurality of segmental forming members adapted to be carried thereon, and a removable liner member adapted to be interposed between the roll spindle and the segments.

3. In a composite roll the combination of a roll spindle, a plurality of removable forming segments, and means to clamp the segments on the roll, of a removable liner member adapted to be positioned between the roll spindle and the segments, and a special segment adapted to fill the gap in the forming surface caused by interposition of the said liner member.

4. In a composite roll comprising a supporting body portion and removable face members adapted to seat thereon, the combination of a removable member adapted to surround the body and be interposed between it and the face members, whereby to vary the diameter of the roll body.

5. A composite roll comprising a body portion having a supporting face, an overhanging undercut collar at one edge of said face member, a removable undercut ring mounted at the other edge of the face member, means to urge the ring toward the fixed collar, removable segments having beveled edges adapted to be clamped on the supporting face by said ring and collar, and a removable liner member adapted to be interposed between the supporting face and segments whereby to vary the diameter of the roll.

6. A composite roll comprising two adjacent series of segmental facing members forming a groove at their meeting edges, a

roll spindle for carrying the said segments, a fixed overhanging abutment engaging the outer edges of one series of segments and a 5 slidable overhanging ring member engaging the outer edges of the other series of segments, and a removable band member adapted to be positioned adjacent to the seg-

ments and to compensate for reduction of the segments caused by redressing thereof.

In testimony whereof, I sign my name.

GEORGE BAEHR.

Witness:

HELEN M. GRIFFIN.
